ARTIFICIAL CHRISTMAS TREE TWIG

William A. Warren, San Bernardino, Calif., assignor to
Warren Christmas Trees, Inc., San Bernardino, Calif.,
a corporation of Nevada

Application April 26, 1956, Serial No. 41,217

Term of patent 14 years

(Cl. D29—1)

Fig. 1

Fig. 3

Fig. 2

Figure 1 is a perspective view of an artificial Christmas tree twig showing my new design.

Figure 2 is a bottom perspective view of the artificial Christmas tree twig.

Figure 3 is an enlarged fragmentary bottom plan view of the artificial Christmas tree twig.

I claim:

The ornamental design for an artificial Christmas tree twig, substantially as shown.
